(57) **CLAIM**

The ornamental design for headphone band with angled shape, as shown and described.

DESCRIPTION

FIG. 1 is a front perspective view of a headphone band with angled shape;

FIG. 2 is a front elevational view thereof;

FIG. 3 is a rear elevational view thereof;

FIG. 4 is an elevated left view thereof;

FIG. 5 is an elevated right view thereof;

FIG. 6 is an top plan view thereof;

FIG. 7 is an elevated bottom view thereof;

FIG. 8 is a perspective view of the headphone band shown in isolation;

FIG. 9 is a facing view of the headphone band shown in isolation;

FIG. 10 is a rear view of the headphone band shown in isolation; and,

FIG. 11 is a bottom plan view of the headphone band shown in isolation.

The dotted lines illustrate environmental features of an exemplary headphone band with angled shape, and form no part of the claimed design.
